(57) **CLAIM**

The ornamental design for a multi-tool, as shown and
described.

DESCRIPTION

FIG. 1 is a perspective view of a multi-tool;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a back view thereof;

FIG. 8 is a perspective view of the multi-tool of FIG. 1 with
a tool extended;

FIG. 9 is a top view thereof;

FIG. 10 is a bottom view thereof;

FIG. 11 is a right side view thereof;

FIG. 12 is a left side view thereof;

FIG. 13 is a front view thereof;

FIG. 14 is a perspective view of the multi-tool of FIG. 1 with
a storage wedge extended

FIG. 15 is a top view thereof;

FIG. 16 is a bottom view thereof;

FIG. 17 is a right side view thereof;

FIG. 18 is a left side view thereof; and,

FIG. 19 is a front view thereof.

The broken lines in the figures represent portions of the
article which form no part of the claimed design.
